MEANS FOR REGULATING THE INTENSITY OF ACTION OF MASSAGING OR EXERCISING MACHINES

Application filed October 5, 1928. Serial No. 310,509.

The general object of this invention is to provide novel means for modifying the action of the belt of an exercising or massaging machine.

5 There are a number of these machines on the market, and they are all characterized by the same general principle of operation, which is that a pair of arms carrying hooks are rapidly reciprocated in alternation back 55 and forth. Loops on the ends of a canvas or other fabric belt are passed over these hooks, with the result that when the belt is passed over the body of the user, it is moved rapidly back and forth, causing the body 60 to be agitated or massaged.

While many of these machines have adjustable features for reducing or increasing the severity of the action of the belt, the adjustment of the machine is not always easy, 20 especially for women, and cannot be effected while the machine is in use. Some makes of these exercising machines have no means whatever for adjusting the degree of the agitating action.

25 Many persons have had operations of one kind or another, leaving the particular part of the body where the operation was performed very sensitive; or some part of the body may be sensitive due to some abnormal 30 condition, and a massaging action of these machines that would be pleasant and stimulating at one part of the body, will be too severe, and even painful, when applied at such a sensitive part of the body. In such 35 cases, the one using the machine must either be content with a gentle action for the whole body, or must interrupt the treatment and adjust the machine to accommodate its motion to some sensitive part of the body.

40 It is the aim of our invention to enable the degree of the exercising or massaging action of the belt employed to be readily adjusted by very simple means and in a very short time, and without the user of the machine having 45 to remove the belt from the machine, or even from his body.

With the above general object in view, our invention consists in applying resilient means 50 to the belt for yieldably drawing the end por-

tions of the belt, or the portions between the body of the user and the machine, toward each other, which we have discovered operates to very decidedly decrease the severity of the action of the belt. Adjustments of the degree 55 of agitation can further be secured by positioning the resilient adjusting device at different points in the end portions thereof, whereby a great range of adjustment in the action of the belt is secured. 60

In an application filed by us on July 11th, 1928, Ser. No. 291,864, we have shown and described and broadly claimed, the use of means for adjusting the end portions of the belt between the body and the machine toward and from each other to vary the intensity of action of the belt on the body. This prior invention also discloses and claims, broadly, locating such means at various points in the belt to procure a wide range of 70 adjustment of the agitating action. The means illustrated in our prior application for accomplishing this purpose was, in one case, a chain, and in the other, a mechanical adjusting device. In the case of the present invention, we find a great improvement in the character of the agitating action is effected by employing resilient means, and we preferably use for this purpose a rubber band connected at its ends to the sides of the belt, 75 or else a coil spring, similarly positioned. 80

In the accompanying drawing—

Figure 1 is a sectional view taken on the line 1—1 of Fig. 2;

Figure 2 is a plan view of an exercising 85 belt with a rubber band shown connected to the two sides of the belt;

Figure 3 is a cross-sectional view on the line 3—3 of Fig. 2;

Figure 4 is a plan view on an enlarged 90 scale showing one of the socket members for receiving the head of the rubber band;

Figure 5 is a view similar to Fig. 2, but showing the use of a coil spring instead of a 95 rubber band;

Figure 6 is a plan view on an enlarged scale showing one end of the coil spring and an eye into which a hook on the end of the spring is secured; and

Figure 7 is a side view slightly in perspec- 100

tive illustrating the manner of using the invention.

Referring now to the drawing, the numeral 1 indicates an exercising belt which, as previously stated, may be made of canvas and which is provided at each end with a loop 2, which loops are adapted to be passed over the hooks 3 (Fig. 7) of an exercising machine 4. When the belt is passed around the body 10 in the manner illustrated in Fig. 7, and the machine placed in operation, the hooks 3, vibrating rapidly in alternation, will cause the belt 1 to be drawn rapidly back and forth on the body of the user, producing a more or less 15 violent agitation of that portion of the body to which the belt is applied, depending upon the degree of severity of the vibrating action employed. We will now describe the means which we employ for regulating the severity 20 of the action of the exercising belt.

The numerals 5, 6 and 7 (Fig. 2) indicate, respectively, corresponding sets of socket members secured in the end portions of the belt 1 at corresponding distances from the 25 ends thereof. That is to say, the corresponding socket members 5 are located at a comparatively short distance from the respective ends of the belt, the socket members 6, at a greater distance, and the socket members 7, 30 at the greatest distance from the ends of the belt. As shown by Fig. 4, each of the socket members comprises a circular body portion 8 having a recess 9 formed therein, a bottom 10, and a slot 11 formed in the front side of 35 the body portion. Apertured flanges 12 project from each side of the body portion 8. In applying the socket member to the belt, a metal plate 13 of the length of the socket member is applied to the outside of the belt, and rivets 14 are passed through the apertured flanges 12 and corresponding apertures 40 in the plate 13.

The numeral 15 indicates a rubber band which is of substantial thickness, such as to 45 require considerable pulling strain to extend it, and on each end of this band is provided a head 16 which is of a size to fit snugly in the corresponding recess 9 of a socket member. The rubber band 15 is of the same width 50 as the belt 1 and when its heads 16 are positioned in one or the other sets of the socket members, the lower ends of the heads will rest upon the bottoms 10 of said socket members and the body or thinner portion of the band 55 will extend through the slots 11 in the socket members. At any time, the user of the machine can readily decrease or increase the degree of vibration effective on the body by removing the rubber band from one set of 60 socket members and securing it in a set of socket members further away or nearer to the body of the user, as the case may be. When the rubber band is placed in the socket members 7, the degree of agitation is considerably less than applies when the band is po-

sitioned in the central set of socket members 6, and the same relative difference exists between the socket members 6 and the socket members 5 as respects the degree of agitation.

In addition to drawing the end portions of the belt toward each other, which in and of itself causes a decrease in the severity of the action of the belt, the use of resilient connecting means for this purpose produces a decided change in the quality of the vibration, 70 which is also in the direction of rendering the action less harsh or severe, and such resilient means also enables the user to automatically secure a wide range of variation in the character or degree of vibration by the simple act 75 of pressing the body outwardly more or less firmly against the exercising belt. This action tends to stretch the rubber band and to separate the end portions of the belt, which will increase the severity of the action; but 80 even when the body is pressed outwardly against the belt with the maximum amount of power, the agitating action of the belt will still be less severe than if the rubber connecting the band were not employed. It is thus 85 possible for one to automatically regulate the degree of the massaging action by simple pressure of the body on the belt. 90

In Fig. 5, we have shown a modification in the resilient means employed for connecting the end portions of the belt, which consists in the employment of a coil spring 17 in place of the rubber band 15. Various means for enabling this coil spring to be connected in adjusted positions on the belt may be utilized. 95 A simple means, and the one which we prefer, is illustrated on an enlarged scale in Fig. 6, in which the spring 17 is provided at each end with a spring hook 18, and each side of the belt is provided with eyes 19 into which these 100 hooks may be inserted. As shown, we employ three of these eyes, 19, 20 and 21, corresponding to the socket members 5, 6 and 7 of Fig. 2, and the spring 17 can be secured in corresponding sets of these eyes, as will be 105 understood.

We wish it understood that while we have shown the best known means of carrying out our invention, we do not wish to be limited to the precise forms of the invention illustrated, 110 as we recognize that other characters of resilient connecting means than those illustrated, and other ways of securing the ends of such resilient connecting means to the belt, could be employed, without departing from 115 the spirit of our invention. 120

We claim:

1. In combination with an exercising belt having an engaging member at each end for attachment to a massaging machine, resilient 125 means carried by and connected with the belt for drawing opposite side portions of the belt between the body and the ends connected to the machine toward each other to vary the intensity of action of the belt on the body. 130

2. In combination with an exercising belt having an engaging member at each end for attachment to a massaging machine, resilient means carried by and detachably connected with the belt for drawing opposite side portions of the belt between the body and the ends connected to the machine toward each other to vary the intensity of action of the belt on the body, and a plurality of means on 10 said belt to permit the resilient means to be adjustably positioned on the belt.

3. In combination with an exercising belt having an engaging member at each end for attachment to a massaging machine, a rubber band having its ends connected to corresponding parts of the opposite sides of the belt between the body and the ends connected to the machine.

4. In combination with an exercising belt 20 having an engaging member at each end for attachment to a massaging machine, a rubber band having its ends detachably connected to corresponding parts of the opposite sides of the belt between the body and the 25 ends connected to the machine.

In testimony whereof, we have hereunto set our hands.

ALFRED D. LUEHRMANN.
FRANCIS X. MEEHAN.
